United States Patent Office

Des. 178,539
Patented Aug. 14, 1956

178,539

PROTECTOR FOR PAINTED HIGHWAY MARKINGS

George T. Robbins, Tuscumbia, Ala., assignor to Robbins
Floor Products, Inc., Tuscumbia, Ala., a corporation of
Alabama

Application February 21, 1956, Serial No. 40,257

Term of patent 14 years

(Cl. D72—1)

Fig. 1 is a top perspective view of a protector for
painted highway markings showing my new design;

Fig. 2 is a bottom perspective view thereof; and

Fig. 3 is an end elevational view thereof.

I claim:

The ornamental design for a protector for painted high-
way markings, as shown.
